(57) **CLAIM**

The ornamental design for an electronic device power bank, as shown and described.

DESCRIPTION

FIG. 1 is a bottom perspective view of an electronic device power bank, showing my new design;

FIG. 2 is a top right perspective view thereof;

FIG. 3 is a front view thereof;

FIG. 4 is a top left perspective view thereof;

FIG. 5 is a rear view thereof;

FIG. 6 is a right side view thereof;

FIG. 7 is a left side view thereof;

FIG. 8 is a bottom view thereof; and,

FIG. 9 is a top view thereof.

The broken lines present in the Figs. are included for the purpose of illustrating portions of the article which form no part of the claimed design.
